C. F. WILLARD.
FUSELAGE CONSTRUCTION.
APPLICATION FILED OCT. 18, 1916.

1,394,459.

Patented Oct. 18, 1921.

Charles F. Willard ^{Inventor}
By his Attorney
Thompson

UNITED STATES PATENT OFFICE.

CHARLES F. WILLARD, OF NEW YORK, N. Y., ASSIGNOR, BY MESNE ASSIGNMENTS, TO L-W-F ENGINEERING COMPANY, INC., OF COLLEGE POINT, LONG ISLAND, NEW YORK, A CORPORATION OF NEW YORK.

FUSELAGE CONSTRUCTION.

1,394,459.

Specification of Letters Patent. Patented Oct. 18, 1921.

Application filed October 18, 1916. Serial No. 126,285.

To all whom it may concern:

Be it known that I, CHARLES F. WILLARD, a citizen of the United States, residing at the borough of Manhattan, in the county of 5 New York and State of New York, have invented certain new and useful Improvements in Fuselage Construction, of which the following is a specification, reference being had therein to the accompanying 10 drawing.

My invention relates to improvements in the construction of the body portion of an aeroplane or the covering therefor, and more particularly consists in arranging successive 15 layers of material in such a manner as to insure tough rigidity and durability.

Referring to the accompanying drawing, I have illustrated part of the body portion or fuselage of an aeroplane in the construction of which I may first use a layer of 20 fabric such as linen indicated by the reference character 2, then at an angle thereto strips of wood, preferably spruce, indicated by the reference character 3, laid parallel and at an angle as shown, then 25 fabric such as strips of linen tape indicated by the reference character 4, also laid parallel and at an opposing angle, then preferably another layer of wood as indicated by the 30 reference character 5 and another layer of, e. g., tape as indicated by the reference character 6, then preferably still another layer of wood indicated by the reference character 7 and finally a layer of fabric such 35 as linen indicated by the reference character 8, which may be drawn over the whole in the form of a stocking as desired. Each of the operations is of course preferably accommodated by an application of shellac, 40 glue or other suitable binding material, thus forming a uniform exceedingly tough and durable and light structure.

Of course it will be understood that various modifications and changes may be made

in the construction and arrangement of parts 45 without departing from the spirit of the invention as claimed.

I claim:

1. A fuselage comprising a plurality of layers of wood, each layer consisting of a 50 plurality of spirally directed wooden strips, a fabric between the wood layers in the form of strips wound at opposing angles to the wood strips, and means for binding them together. 55

2. A structure of the class described comprising alternate layers of wood and fabric, said layers applied in strips wound at opposing angles and means for binding same together and the whole covered by a uniform 60 layer of fabric. 60

3. A fuselage comprising a plurality of layers of wood, each layer consisting of a plurality of spirally directed wooden strips, and fabric between the wood layers and 65 means for binding them together.

4. A fuselage body comprising layers of wood and fabric alternating with each other, said layers consisting of strips wound at substantially equal opposing angles to each 70 other, and means for binding said layers together. 70

5. A fuselage comprising a plurality of layers of wood, each of said layers consisting of a plurality of spirally directed 75 wooden strips, the strips of successive layers of wood being wound substantially in spirals of varying pitch, and layers of fabric interposed respectively between said above-mentioned layers, together with means for binding together all of said layers. 80

In testimony whereof I hereunto affix my signature in the presence of two witnesses:

CHARLES F. WILLARD.

Witnesses:

ANNA F. DUFFY,
THOMAS A. HILL.
